BOTTLE

Brooks D. Fuerst, Sylvania, Ohio, assignor to Owens-Illinois Glass Company, Toledo, Ohio, a corporation of Ohio

Filed Feb. 1, 1961, Ser. No. 63,796

Term of patent 14 years

(Cl. D58—8)

The side and end not shown are the same as the respective side and end shown.

I claim:

The ornamental design for a bottle, substantially as shown and described.
